FISH LURE

Earle Richard Cacpal, Sun Valley, Calif.

Application February 14, 1958, Serial No. 49,648

Term of patent 14 years

(Cl. D31—4)

Figure 1 is a top plan view of a fish lure, showing my new design;

Figure 2 is a side elevation view of Figure 1;

Figure 3 is a side elevation view of Figure 2, facing the other way;

Figure 4 is a section taken on the line 4—4 of Figure 2;

Figure 5 is a section taken on the line 5—5 of Figure 2; and

Figure 6 is a magnified section taken on the line 5—5 of Figure 2.

The essential features of my new design are shown in full lines on the drawing.

I claim:

The ornamental design for a fish lure, as shown and described.
